Attorneys.

UNITED STATES PATENT OFFICE.

GEORGE D. LYNCH, OF PITTSFIELD, ILLINOIS, ASSIGNOR OF ONE-HALF TO
WILLARD G. JAMES, OF SAME PLACE.

HORSESHOE.

SPECIFICATION forming part of Letters Patent No. 451,332, dated April 28, 1891.

Application filed August 15, 1890. Serial No. 362,095. (No model.)

To all whom it may concern:

Be it known that I, GEORGE D. LYNCH, a citizen of the United States, and a resident of Pittsfield, in the county of Pike and State of Illinois, have invented certain new and useful Improvements in Horseshoes; and I do hereby declare that the following is a full, clear, and exact description of the invention, which will enable others skilled in the art to 10 which it appertains to make and use the same.

My invention has relation to improvements in horseshoes. Devices of this character as ordinarily constructed provide no means whereby the jar upon the horse incident to 15 travel over pavements, turnpikes, and hard roads is relieved.

It is the primary object of my invention to provide a construction which will secure the above-named desirable ends in a simple and 20 efficient manner; and with this object and others in view the invention consists in the improved construction and combination of parts, as hereinafter more fully set forth and described.

25 In the accompanying drawings, Figure 1 is a perspective view of the complete device. Fig. 2 is an inverted plan of the shoe proper. Fig. 3 is a plan view of the under spring; and Fig. 4 is a cross-sectional view on the 30 line $x-x$, Fig. 1.

Like letters of reference refer to like parts throughout the several figures of the drawings.

Referring to the drawings, the letter A indicates the shoe proper provided at its heels with apertured calks $a-a$, and also provided upon its under face, between the heels or toe or upon the quarters, with inwardly-extending meeting bevels $a'-a'$, the latter having the 35 usual nail-holes a^2-a^3 . The toe of the shoe proper is provided with a re-enforcement or enlargement a^3 , the function of which will appear hereinafter.

The letter B indicates an under spring 45 conforming in shape to the shoe proper and provided at its ends or heels with tenons $b-b$, which fit into the rectangular apertures of the calks. This spring is curved downwardly at opposite points beneath the quarters of the 50 shoe proper, as indicated at $b'-b'$, while its

central portion, or that portion which registers with the toe of the shoe, is provided upon its outer edge with clamping-lugs b^2-b^3 and upon its inner edge with a similar lug b^3 , all of said lugs extending upwardly and adapted to 55 firmly clamp the re-enforced or enlarged portion of the toe of the shoe, so as to securely connect the parts. This spring is furthermore provided with two or more nail-holes b^4 , which register with corresponding holes a^4 in 60 the toe of the shoe.

From the foregoing description the construction of my improved horseshoe will be readily understood.

It will be seen that the two sections when 65 secured together form a most comfortable and yielding shoe, and the dirt is prevented from clogging between the sections by reason of the inwardly-extending meeting bevels upon the under face of the shoe proper, which 70 serve to deflect the dirt or throw it aside when it enters between the sections.

In adjusting the device to a horse's hoof the shoe proper is first secured in position, after which the spring may be readily inserted by passing the tenons through their appropriate apertures in the calks and clamping the front portions together. The 75 nails are then driven through the registering-nail-holes in the spring and shoe. 80

I claim that my device will relieve the jar upon the horse to such an extent as to prevent stiffness of the joints; also relieve horses that are afflicted with corns or analogous maladies, and, if desired, can be employed as 85 a substitute for toe-weights in speed-horses. Furthermore, my invention is exceedingly simple in construction and readily adjusted to the shoe.

Having thus described my invention, what 90 I claim, and desire to secure by Letters Patent of the United States, is—

1. In a horseshoe, the combination, with the shoe proper having apertured heel-calks, of a spring bowed or sprung beneath the quarters of the shoe and provided with end tenons fitting in the apertures of the calks, substantially as set forth. 95

2. In a horseshoe, the combination, with the shoe proper having apertured heel-calks, 100

of a spring having its ends provided with tenons fitting in said apertures and also provided at its forward portion or toe upon opposite edges with upwardly-extending clamping-lugs, substantially as set forth.

3. In a horseshoe, the combination, with the shoe proper having apertured heel-calks and also having its toe re-enforced or enlarged upon its under face, of a spring having its ends provided with tenons fitting in said apertures and provided at its forward portion or toe and upon opposite edges with upwardly-extending lugs adapted to clamp

the re-enforced or enlarged portion of the toe of the shoe, said toe and the corresponding part of the spring being also provided with registering holes for the reception of nails, substantially as set forth.

In testimony that I claim the foregoing as my own I have hereunto affixed my signature ¹⁵ in presence of two witnesses.

GEORGE D. LYNCH.
